UNITED STATES PATENT OFFICE.

MURRAY A. WACHS, OF BROOKLYN, NEW YORK.

METAL-BINDING MACHINE.

Application filed July 11, 1924. Serial No. 725,464.

To all whom it may concern:

Be it known that I, MURRAY A. WACHS, a citizen of the United States, and resident of the city of New York, borough of Brooklyn, in the county of Kings and State of New York, have invented a new and Improved Metal-Binding Machine, of which the following is a full, clear, and exact description.

This invention has relation to metal binding machines and refers more particularly to a machine for attaching metallic binding elements to the corners or edges of articles such as pocketbooks or the like, the same being in the nature of an improvement of my co-pending application filed May 6, 1924, and bearing Serial Number 711,404.

Broadly this invention comprehends an improvement in a machine of this character for attaching or affixing binding elements particularly of an ornamental nature to the corners or edges of articles such as pocketbooks or the like.

One of the outstanding objects of the present invention is to provide an improved machine of this nature, in which means is provided for flushing the bight of the binding element with the edges of the article or material to which it is applied whereby to eliminate the projection or extension of the binding element beyond the edge of the article.

As a further object the invention contemplates in connection with a machine of the character set forth means for controlling or regulating the flushing means to compensate for variations in the thickness of the material from which the bight is formed.

As a still further object the invention contemplates a means for compensating for differences in the thickness of the adjacent edges of an article, when a corner clip is being applied thereto, in order to equalize the pressure of the binding member during the binding operation and to insure an even gripping of the same throughout.

The invention furthermore contemplates a means for adjustably limiting the movement of the binding element whereby the same may be set for use in connection with binding elements or clips and articles to which they are applied in which the combined thickness thereof varies.

Other objects of the invention reside in the provision of a machine of the character set forth which is comparatively simple in

its construction and mode of operation, which is inexpensive to manufacture and operate and which is highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims are expressed.

In the drawings—

Figure 1 is a perspective view of the machine;

Fig. 2 is a similar view of a corner clip which is applied or affixed by the machine to an article;

Fig. 3 is a detail sectional view taken approximately on the line 3—3 on Fig. 2 and illustrating the manner in which the binding element or clip is associated with the article to which it is applied for affixing by the machine;

Fig. 4 is a sectional plan view through the machine taken approximately on the line indicated at 4—4 in Fig. 5;

Fig. 5 is a fragmentary vertical sectional view taken approximately on the line indicated at 5—5 in Fig. 4 and illustrating the article holding means in engagement with the article and the initial engagement of the flushing means with the binding element or clip;

Fig. 6 is a diagrammatical plan view illustrating the initial engagement of the flushing means with the binding element or clip;

Fig. 7 is a fragmentary vertical sectional view similar to Fig. 5 illustrating the final flushing operation of the flushing means;

Fig. 8 is a diagrammatical plan view of the final movement of the flushing means;

Fig. 9 is a view similar to Fig. 7 illustrating the final movement of the binding means;

Fig. 10 is a fragmentary vertical sectional view illustrating the means for compensating for variation in the thickness of different adjacent edges of the material to which a corner clip is applied; and

Fig. 11 is a fragmentary detail sectional view of the latter means.

Referring to the drawings by characters of reference the machine includes a base 10, an upstanding arm 11 at one end of the base having a horizontal overhanging end 12 provided with an upwardly projecting bifurcated terminal 13 the furcations 14, of which are provided with aligned apertures 15 to receive therebetween the apertured end 16 of an operating lever 16 which is fulcrumed thereto by a transverse pivot pin 17. The horizontal overhanging portion 12 of the arm 11 of the machine is provided with a vertical bearing opening through which a plunger rod 18 extends and is vertically movable. The plunger rod has secured thereto a collar 19 at the portion of the rod which extends below the horizontal portion 12 of the arm and which is designed to coact with the underside of the portion 12 to limit the upward vertical movement thereof. Adjacent its upper end, the plunger rod 18 is provided with a suitable element in the nature of a transverse pin 20 between which and the upper side of the portion 12 a coiled expansion spring 21 is interposed for normally elevating the plunger rod to the limit of its upward movement. The upper terminal of the plunger rod 18 is of semispherical formation as illustrated at 22 and is designed to fit in an arcuate recess 23 on the under side of the lever 16. Under this arrangement it will be observed that downward swinging movement of the lever 16 either by hand or foot power will effect a downward movement of the plunger rod against the action of the spring 21. A head 24 is secured to the lower end of the plunger rod for movement therewith and said head is provided with an upwardly projecting guide rod 25 extending through a vertical guide opening 26 in the horizontal overhanging portion 12 of the machine arm, whereby to prevent rotary movement of the head and plunger rod and guide the same in a vertical path of movement only. At its forward end the head 24 is provided with a binding or pressure foot 27 which in the present instance includes forwardly and outwardly divergent wings 28 defining a V-shaped recess at the forward end of the head. In order to provide means for positively holding the pocketbook or other article to which the binding elements are to be applied, in immovable relation to the base, a holding member 29 is employed which is provided with complementary divergent outer faces 30 which are snugly received within the V-shaped notch defined by the wings 28. The holding member 29 is provided with a stem 31 which extends upwardly through the aligned apertures 32 and 33 formed respectively in the radial arm 34 of the collar 19 and in the overhanging portion 12 of the machine arm 11. A stop pin 35 extends

transversely through the stem 31 above the radial arm 34 for the purpose of limiting the downward movement of the holding member 29 relative to the head 24 and binding member 28. A coiled expansion spring 36 surrounds the stem and is interposed between the member 29 and the radial arm 34 for normally projecting the member 29 downwardly and yieldably maintaining the member 29 in a downwardly spaced relation from the radial arm 34, with the stop pin 35 in engagement with said arm. 70

The flushing means consists of a horizontally disposed plate 40 which is arranged for forward and rearward sliding movement in flat contact with the upper face of the base 10, the same being formed at its rear end with a cross bar 41 having rearwardly projecting guide stems 42 which extend through horizontal guide openings 43 in the machine arm 11. The rear arms of the guide stems 42 project beyond the rear side of the machine arm 11 and are provided with suitable pins 44 extending transversely therethrough, between which in the rear face of the arms coiled expansion springs 45 are interposed for normally retracting the plate 40 or moving the same rearwardly whereby its rear end provided with the cross-bar 41 is impinged against the forward lower portion of the machine arm 11. The medial portion of the cross-bar 41 is provided with a rear recess 46 having an upwardly and forwardly inclined cam face 47. The rear end of the head 24 is provided with a rearwardly projecting tail 48 which extends over the cross-bar 41 and a vertically adjustable cam pin 49 depends from the tail 48 for engaging the cam face 47. The cam pin is preferably threaded throughout the major portion of its length as at 50 and is provided with a kerf 51 at its upper end whereby a screwdriver may be engaged therewith for effecting vertical adjustments thereof. A binding nut 52 is threaded over the upper end of the cam pin for locking the same in its vertically adjusted position. 90

In order to provide means for facilitating the proper positioning of the article with respect to the holding member 29, gage elements 55 are employed which consist of slotted bases 56 arranged in flat contact with the upper surface of the machine base 10, said bases having retaining screws 57 extending through the slots thereof and anchored in the base 10. At one end the base is provided with an upstanding gage flange 58 against which the edges of the article are adapted to abut. In order to provide means for gripping and maintaining the article in abutting relation to the gaged flanges 58, leaf-springs 59 are employed which are anchored as at 60 at the upper face of the base and are provided at their free end with upwardly curved terminals 61. 100

The article A as illustrated in Figs. 3, 6 and 8 to which the binding clip or element B is to be applied and attached initially has the element B arranged in juncture position 5 thereon. The binding elements or clips B as particularly illustrated in Fig. 2 are of substantially U-shape in cross-section and consist of a bight portion C connecting substantially parallel flanges D and E. The 10 flange D is formed at its free edge with anchoring means such as spurs F and the portion of the edges which carry the anchoring means are initially disposed in a sufficiently opened up relation to the opposite 15 flange E to readily permit of the engagement of the clip or binding element over the edge of the article A. The machine constituting the invention is designed for the purpose of bending the opened up portions 20 downwardly whereby the flanges D and E of the binding element or clips when applied will be disposed in parallel relation to embrace the opposite faces of the article A with the bight C in bracing the 25 edge of said article. The machine further functions to embed the anchoring means or spurs F in the article A to lock the binding elements or clips in place thereon.

In use and operation of the machine the 30 gage elements 55 are properly set; the operator then positions the article A with the applied clip or binding element B on the upper surface of the base or bed 10 of the machine whereby the edges of the article abut the 35 gage flanges 58 and the leaf springs cramp the article initially in place. The operator then by exerting a downward pressure on the lever 16 moves the plunger rod 18 and its head 24 downwardly which initially effects 40 the impingement of the holding member 29 into engagement with the article due to the fact that the lower edge of the holding member 29 is normally projected below the lower edge of the binding member 28 by the spring 36. The holding member 29 thus further grips and maintains the article with its applied clip in immovable relation to the base or bed 10. Further continued 45 downward pressure on the lever 16 effects a further downward movement of the plunger rod 18 and the head 24. The next operation consists of a forward movement of the flushing plate 40 which due to the 50 interengagement of the cam pin 49 with the cam face 47 of the cross-bar 41 is advanced forwardly to force the bight C of the clip or binding element until the bight is flush with the edges of the article. Immediately 55 following a completion of the flushing operation a further continued downward movement of the head 24 brings the binding or pressure foot 27 into engagement with the 60 opened up portions of the clip or binding element to bend the same downwardly and embed and anchor the spurs F in the article A.

In order to prevent crushing of the binding element or clip by limiting the final downward movement of the head and pressure foot, a stock member 65 is employed which may consist of a pin threadedly engaged in 70 a socket in the overhanging portion 12 of the machine arm, with which the underside of the lever 16 is adapted to engage. The stop member 65 is vertically adjustable in 75 order to regulate the limitation of the downward movement of the lever 16, plunger rod 18 and plunger head 24 whereby the machine may be adjusted to compensate for various combined thicknesses in the binding elements or clips and the articles to which they 80 are applied.

In many instances where corner clips or binding elements are applied, one of the adjacent edges of the article is of lesser thickness than the other, and in order to provide 85 means for compensating therefor to equalize the pressure of the pressure or binding foot 27, shim arms 66 are provided at the extremity of pivoted levers 68 which are fulcrumed on vertical pins 69 anchored in the 90 upper face or bed 10. The levers 68 in addition to being mounted on the pin for turning movement are mounted thereon for rocking movement vertically by interposing 95 between the underside of the lever and the upper surface of the base a coiled expansion spring 70 and by interposing between the upper side of the lever and transverse stop pins 71 coiled expansion springs 72. The springs 100 72 have one of the end convolutions hooked over the edge of the lever 68 as at 73 with the opposite end convolution suitably attached to the pin whereby the lever is normally swung to a position to throw the shim arm 66 to an out of the way position. When 105 it is desired to use the shim arm the lever is swung on its pivot to dispose the same in the position illustrated in dotted lines in Fig. 4. This position is obtained by engagement of the lever with the stop pin 74 whereby the shim arm directly overlies and 110 is disposed in the path of movement of the pressure or binding foot 27. When the lever 68 is released it will be noted that the spring 72 turns the same on its pivot until the free end of the lever is arrested from 115 further movement by engagement with the gage flanges 58 of the gage elements 55.

After the attaching or affixing operation 120 is completed, the release of pressure on the lever 16 permits the plunger spring 21 to return the lever, plunger rod, plunger head 24, pressure foot 27 and holding member 29 to normal position while the disengagement of the cam pin 49 in the cam face 47 permits the springs 45 to react the flushing plate 40.

While the form of machine illustrated is 125 particularly designed for the application of corner clips, it is of course to be understood 130

that the scope of the claims is such as to cover a similar machine where the binding elements or clips are attached to a straight edge, in which instance the pressure foot, holding member 29 and the forward edge of the flushing plate 40 will be in a straight line for this purpose. It will be further obvious that the gage elements 55 and leaf springs 59 will be accordingly moved back 10 in position in proper alinement therewith.

I claim:

1. A machine for attaching substantially U-shaped binding elements or clips having a pair of walls joined by a bight portion to 15 the edges of a piece of material, comprising a base for supporting the piece of material and the elements to be attached thereto, means for holding the material against relative movement on the base, means for advancing said element to dispose and hold the bight portion flush with the outer edge 20 of the material, and means movable toward the base for subsequently exerting a pressure against the element or clip to bind the 25 same to the material.

2. A machine for attaching to the edges of a piece of material substantially U-shaped binding elements or clips having opened-up portions formed with anchoring 30 spurs and connected by a bight, said machine comprising a base for supporting the piece of material and the elements to be attached thereto, means for holding the material against relative movement on the base, 35 means for advancing said element to dispose and hold the bight flush with the outer edge of the material, and means movable toward the base for subsequently exerting a pressure against the element or clip to bind the 40 same to the material.

3. In a machine for facilitating the attachment of substantially U-shaped binding elements having opened-up portions formed with anchoring spurs to the edges or 45 corners of pocketbooks or similar articles, a base for supporting the article and binding element thereon, a gripping member movable into engagement with said article for holding the same immovable on the base, 50 means for flushing the bight of said elements with the edges of the article and for holding the same in flushed relation thereto, and a pressure or binding member movable toward the base for effecting the bending 55 of the opened-up portions and the embedding of the anchoring spurs in the article.

4. In a machine for facilitating the attachment of substantially U-shaped binding elements having opened-up portions 60 formed with anchoring spurs to the edges or corner of pocketbooks or similar articles, a base for supporting the article and binding element thereon, a gripping member movable into engagement with said article 65 for holding the same immovable on the base,

means for flushing the bight of said elements with the edges of the article and for holding the same in flushed relation thereto, a pressure or binding member movable toward the base for effecting the bending of 70 the opened-up portions and the embedding of the anchoring spurs in the article, and a common actuating member operable to successively actuate the gripping member, the flushing means, and binding member. 75

5. In a machine for facilitating the attachment of substantially U-shaped binding elements having opened-up portions formed with anchoring spurs to the edges or corners of pocketbooks or similar articles, a base for supporting the article and binding element thereon, a gripping member movable into engagement with said article for holding the same immovable on the base, means for flushing the bight of said elements with the edges of the article and for holding the same in flushed relation thereto, 80 a pressure or binding member movable toward the base for effecting the bending of the opened-up portions and the embedding of the anchoring spurs in the article a common actuating member operable to successively actuate the gripping member, the flushing means, and the binding member, 85 and an adjustable stop member engageable with the actuating member to limit its final movement whereby to regulate the operation of the binding member to compensate for various thicknesses of the articles and binding elements. 90

6. In a machine for facilitating the attachment of substantially U-shaped binding elements having opened-up portions formed with anchoring spurs to the edges or corners of pocketbooks or similar articles, a base for supporting the article and binding element thereon, a gripping member movable into engagement with said article for holding the same immovable on the base, means for flushing the bight of said elements with the edges of the article and for holding the same in flushed relation thereto, a pressure or binding member movable toward the base for effecting the bending of 105 the opened-up portions and the embedding of the anchoring spurs in the article, a common actuating member operable to successively actuate the gripping member, the flushing means, and the binding member, and an adjustable stop member engageable with the actuating member to limit its final movement whereby to regulate the operation of the binding member to compensate for various thicknesses of the articles and binding elements, 110 and adjustable means on the actuating member for regulating the movement of the flushing means whereby to compensate for various thicknesses of the bights of the binding elements. 120

7. In a machine for facilitating the at-

- attachment of ornamental corner clips of cross-sectional U-shape configuration and having opened-up portions formed with anchoring spurs to the adjacent edges of pocketbooks or similar articles, a base for supporting the article and corner clip thereon, a gripping member movable into engagement with said article for holding the same immovable on the base, a pressure member movable toward the base for effecting the bending of the opened-up portions and the embedding of the anchoring spurs in the article, a common actuating member operable to successively actuate the gripping member and the pressure member, and means for compensating for relative thicknesses of the adjacent edges defining the corner of the article.
8. In a machine for facilitating the attachment of ornamental corner clips of cross-sectional U-shape configuration and having opened-up portions formed with anchoring spurs to the adjacent edges of pocketbooks or similar articles, a base for supporting the article and corner clip thereon, a gripping member movable into engagement with said article for holding the same immovable on the base, a pressure member movable toward the base for effecting the bending of the opened-up portions and the embedding of the anchoring spurs in the article, a common actuating member operable to successively actuate the gripping member and the pressure member, and means for compensating for relative thicknesses of the adjacent edges defining the corner of the article, said means comprising a member pivoted for horizontal and vertical movement on the base having a shim arm adapted to be swung to a position to overlie the thinner edge of the corner and in the path of movement of the pressure element, and means for normally swinging said member to an out of the way position.
9. In a machine for facilitating the attachment of ornamental corner clips of cross-sectional U-shape configuration and having opened-up portions formed with anchoring spurs to the adjacent edges of pocketbooks or similar articles, a base for supporting the article and corner clip thereon, a gripping member movable into engagement with said article for holding the same immovable on the base, a pressure member movable toward the base for effecting the bending of the opened-up portions and the embedding of the anchoring spurs in the article, a common actuating member operable to successively actuate the gripping member and the pressure member, and means for compensating for relative thicknesses of the adjacent edges defining the corner of the article, said means comprising a member pivoted for horizontal and vertical movement on the base having a shim arm adapted to be swung to a position to overlie the thinner edge of the corner and in the path of movement of the pressure element.
10. In a machine for facilitating the attachment of substantially U-shaped binding elements having opened-up portions formed with anchoring spurs to the edges or corners of pocketbooks or similar articles, a base for supporting the article and binding element thereon, a gripping member movable into engagement with said article for holding the same immovable on the base, means for flushing the bight of said elements with the edges of the article and for holding the same in flushed relation thereto, a pressure or binding member movable toward the base for effecting the bending of the opened-up portions and the embedding of the anchoring spurs in the article, and gage elements mounted on the base for facilitating the positioning of the article with respect to the gripping, flushing, and binding means.

MURRAY A. WACHS.
